UNITED STATES PATENT OFFICE.

AGNES SNYDER, OF DULUTH, MINNESOTA.

COLLAR-BUTTON NOTCH.

1,290,672.

Specification of Letters Patent.

Patented Jan. 7, 1919.

Application filed April 29, 1918. Serial No. 231,385.

To all whom it may concern:

Be it known that I, AGNES SNYDER, a citizen of the United States, residing at Duluth, in the county of St. Louis, State 5 of Minnesota, have invented a new and useful Collar-Button Notch; and I do hereby declare the following to be a full, clear, and exact description of the invention, such as will enable others skilled in the art to which 10 it appertains to make and use the same.

The present invention relates to a button hole construction, and has for its object to provide a device of this character which is especially adapted for use in connection with 15 collars and similar articles of apparel which are ordinarily held in position by double headed buttons, such as collar buttons, the object of the invention being to provide a novel button hole which can be placed in 20 engagement with a collar button without any of the annoyance which is frequently incident to inserting a collar button through an ordinary button hole.

Further objects of the invention are to 25 provide a button hole construction which will not materially increase the cost of the collar or other article of apparel in which it is embodied, which can be quickly engaged with or disengaged from a collar button, and which will enable the collar or 30 other article of apparel to be held firmly in position by means of the collar button.

With these and other objects in view, the invention consists in certain novel combinations and arrangements of the parts as will 35 more fully appear as the description proceeds, the novel features thereof being pointed out in the appended claim.

For a full understanding of the invention, 40 reference is to be had to the following description and accompanying drawings, in which:—

Figure 1 is a plan view of a collar provided with button holes constructed in accordance with the invention.

Fig. 2 is an enlarged detail view of one end of the collar.

Fig. 3 is a similar view of the middle portion of the collar.

50 Corresponding and like parts are referred to in the following description and indicated in all the views of the drawings by the same reference characters.

While the button hole construction may be 55 used to advantage in connection with any article of apparel which is to be secured in

position by the use of a collar button, it has been shown for the purpose of illustration as embodied in a turn down collar of which the numeral 1 designates the back or body 60 portion, and the numeral 2 the turn down or flap portion. One of the end tongues is provided with a conventional button hole 3, the other end tongue being provided with a small opening 4 and a large upwardly offset 65 opening 5. The opening 4 is of just the proper size to receive the shank of an ordinary collar button, while the opening 5 is sufficiently large to admit of the head of a collar button being inserted through the 70 same. These two openings are connected by a tortuous or angular slot 6 through which the shank of the collar button can be readily moved from one of the openings to the other opening. At the intersection of the 75 smaller opening 4 and the slot 6 a pair of rounded ears 7 are provided, said ears having an opposed relation and coöperating with each other to provide a contracted throat between the slot and the smaller 80 opening. These ears 4 can be flexed or bent to admit of the shank of the collar button being forcibly moved into or out of the small opening 4, although they operate in an effective manner to prevent the shank of 85 the collar button from working its way out of the small opening 4 while the collar is being worn. The middle of the back 1 of the collar is provided with a small opening 8 and a longitudinally offset large opening 90 9, said openings being connected as in the previous instance by a narrow tortuous or angular slot 10, and rounded ears 11 being provided at the intersection of the narrow 95 slot and small opening. The large opening 95 9 is offset longitudinally from the small opening 8, for the reason that the back of the collar is fastened in position before the end flaps are secured, and the collar can readily be moved longitudinally at that time 100 to shift the shank of the collar button from the larger opening 9 into the smaller opening 8. After the back of the collar has been secured the end tongue provided with the usual button hole 3 is fastened in position. There is seldom any difficulty in fastening the first end tongue upon the collar button, and an ordinary button hole is accordingly satisfactory at this place. After 105 the first end tongue has been secured to the 110 collar button the large opening 5 of the other end tongue is slipped over the head

of the collar button and the shank of the collar button worked through the angular slot 6 into the small opening 4. This can be accomplished without difficulty or annoyance, and the collar is then fastened securely in position.

Having thus described the invention, what I claim as new and desire to secure by Letters Patent, is:—

- 10 The herein described button hole construction adapted for engagement with a collar button, said construction including a small opening of a size to receive the button shank and a large opening of a size to receive the button head, said openings having a spaced relation and being connected by a narrow slot formed with a series of short straight portions intersecting each other at
- 15

sharp angles and through which the shank of the button can be moved from one opening to the other opening, and narrow rounded ears projecting into the narrow slot at the junction thereof with the small opening, said ears being flexible and coöperating with each other to provide a restricted passage through which the shank of the button can be forcibly pushed, although it is locked against accidental movement out of the small opening.

In testimony whereof I have signed my name to this specification in the presence of two subscribing witnesses.

MRS. AGNES SNYDER.

Witnesses:

J. GEO. HANSON,
B. J. SNYDER.
